UNITED STATES PATENT OFFICE.

PAUL BURKE, OF GREEN BAY, WISCONSIN, ASSIGNOR TO NORTHWEST ENGINEERING COMPANY, OF GREEN BAY, WISCONSIN, A CORPORATION OF WISCONSIN.

POWER SHOVEL.

Original application filed December 18, 1922, Serial No. 607,510. Divided and this application filed March 14, 1924. Serial No. 699,319.

To all whom it may concern:

Be it known that I, PAUL BURKE, a citizen of the United States of America, and resident of Green Bay, in the county of Brown and State of Wisconsin, have invented new and useful Improvements in Power Shovels, of which the following is a description, reference being had to the accompanying drawings, which are a part of this specification.

This invention relates to power shovels, and more particularly to that type of shovel in which the hoisting cable is used to actuate the thrusting mechanism.

15 The object of the invention is to improve and simplify power shovels of the rope-thrusting type and to provide for the thrusting of the dipper handle without the use of gear mechanism, or rack and pinions, 20 or auxiliary driving apparatus of any kind.

A further object of the invention is to provide a power shovel of the rope-thrusting type in which the hoisting rope is also used to thrust the dipper handle outwardly and 25 is directly associated therewith, and in which a separately controlled cable is used to retract the dipper handle.

This application is a division from my copending application Serial No. 607,510, 30 filed December 18, 1922.

The invention further consists in the several features hereinafter set forth and more particularly defined by claims at the conclusion hereof.

35 In the drawings: Fig. 1 is a side elevation view of a power shovel mechanism embodying the invention; Fig. 2 is a plan view thereof.

In the drawings the numeral 4 designates 40 a boom, which may be of any suitable construction, vertically pivotally attached at its lower end to the rotating base 5 of the machine, which base is of well known construction. A hoisting drum 6 and an auxiliary drum 7 are mounted on the base in any suitable manner and driven from a prime mover, not shown, on the base. The drums 6 and 7 may be of any well known construction equipped with clutches and brakes to control their operation. The boom is adapted to be raised or lowered and held in various positions of vertical adjustment by any well known means, such as a cable 8 connecting pulleys 9 at the outer end of the

boom to parts on the rotating base. The boom 55 shown is of the plate girder type with the dipper handle 10 working between its sides.

A shipper shaft 11 is preferably secured in brackets 12 on the boom 4 and the saddle blocks 13 are loose on the shaft. The dipper handle shown is made in two sections and has a metal covering 14. Each section of the handle is mounted to slide between the adjacent saddle block and a flanged roller 15 on the shipper shaft. A two-part drum or sheave 16 is preferably journalled on the shipper shaft between the rollers 15. The dipper or shovel 17 may be of any suitable construction and is mounted, as usual, at the lower end of the dipper handle. 70

The hoisting cable 18 is dead-ended on the drum 6, passes therefrom beneath a guide pulley 19 and over a pulley 20 at the outer end of the boom, then around a padlock sheave 21 carried by the dipper, then 75 once or more times around a drum 22, thence rearwardly and over the sheave 16 on the shipper shaft 11, and is dead-ended at 25 near the upper end of the dipper-stick 10. A cable 26 secured to and wound upon the 80 drum 7 passes over a sheave 27 conveniently formed as a part of the drum, 16, and is dead-ended near the dipper, as at 28.

With the construction above described, when the drum 7 is prevented from turning, 85 by its brake, thereby holding the line or cable 26, and the line 18 is pulled in, the dipper moves approximately in the arc of a circle of which the shipper shaft is the center. If it is desired to crowd farther in to the bank or to move the dipper farther out, as in loading a wagon, the braking effect on line 26 is released slightly so as to allow cable 26 to pay out and cable 18 is wound in, causing the dipper pivoted to the 90 shaft 11 to swing relative to said shaft and shift outwardly with respect to the boom. Conversely, if it is desired to move the dipper farther in, releasing the brake on line 18 and hoisting with line 26 produces this 95 effect. Thus, by a proper manipulation of the lines 18 and 26 any desired swinging or thrusting movement of the dipper and its stick may be effected. Furthermore, since the line 18 which effects the thrust is actuated by the hoist, a crowding effect equal to the full driving force of the engine is 100 secured. 105

It will be noted that the thrusting action on the dipper is proportional to the load upon the dipper due to the resistance and weight of the material it encounters during digging.

5 I desire it to be understood that this invention is not to be limited to any specific form or arrangement of parts except in so far as such limitations are specified in the 10 claims.

What I claim as my invention is:

1. In an excavating shovel, the combination with a supporting boom, of a dipper and dipper handle mounted thereon to move bodily 15 lengthwise and swing with respect thereto, a dipper-hoisting-and-thrusting cable associated with said dipper and dipper handle and acting directly thereon principally lengthwise of said handle in all its positions for 20 crowding the dipper into the material to be excavated, and means distinct from said cable for moving said dipper inwardly.

2. In an excavating shovel, the combination with a supporting boom, of a dipper 25 and dipper handle, a swinging support pivotally connected to the boom and in which the dipper handle reciprocates and with which it swings, a dipper-hoisting-and-thrusting cable associated with said dipper 30 and dipper handle and acting directly thereon principally lengthwise of said handle in all its positions for crowding the dipper into the material to be excavated, and means distinct from said cable for moving said dipper 35 inwardly.

3. In an excavating shovel, the combination with a supporting boom, of a dipper and its handle, a swinging support pivotally connected to the boom and in which the 40 dipper handle reciprocates and with which it swings, a dipper-hoisting-and-thrusting cable connected with the dipper and its handle and acting directly thereon principally lengthwise of said handle in all its positions 45 for crowding the dipper into the material to be excavated, and a separately controlled cable for retracting the dipper.

4. In an excavating shovel, the combination with a supporting boom, of a dipper 50 and dipper handle mounted thereon to move lengthwise and swing with respect thereto, a dipper-hoisting-and-thrusting cable associated with said dipper and dipper handle and acting directly thereon for crowding 55 the dipper into the material to be excavated and having a multi-part hoisting line portion between the dipper and the boom, and means distinct from said cable for moving said dipper handle inwardly.

60 5. In an excavating shovel, the combination with a supporting boom, of a dipper and its handle, a shipper shaft, a swinging support pivotally mounted on said shaft and in which the dipper handle reciprocates and 65 with which it swings, a dipper-hoisting-and-

thrusting cable connected to the dipper and its handle and acting directly thereon for crowding the dipper into the material to be excavated, guide means on said shipper shaft about which a portion of said cable 70 runs, said guide means disposing the run of the cable between it and the dipper handle substantially parallel to said handle, a separately controlled cable for retracting the dipper, and guide means for said last-named 75 cable over which said cable passes and disposing the run from said guide means to said dipper handle substantially parallel thereto.

6. In a power shovel, the combination of 80 a boom, a dipper and dipper handle, a pivotal support on said boom for slidably receiving said handle, a dipper hoisting cable connected with said dipper and having a portion extending between said support and the inner end of said handle to shift said handle outwardly and means for shifting said handle inwardly.

7. In a power shovel the combination of a 85 boom, a dipper and dipper handle, a pivotal support on said boom for slidably receiving said handle, a dipper hoisting cable connected with said dipper and having a portion extending between the axis of said support and the inner end of said handle to 90 shift said handle outwardly, and means for shifting said handle inwardly.

8. In a power shovel the combination of a 95 boom, a dipper and dipper handle mounted thereon for swinging and bodily lengthwise shifting movements, a dipper hoisting cable operatively associated with the outer end of said handle for raising and lowering said dipper and with the inner end of said handle at a fixed point thereon for shifting 100 said handle outwardly only, and means distinct from said cable for controlling such shifting movement and for shifting said handle inwardly.

9. In a power shovel the combination of a 105 boom, a dipper and dipper handle mounted thereon for swinging and bodily lengthwise shifting movements, a dipper hoisting cable operatively associated with the outer end of said handle for raising and lowering said 110 dipper and with the inner end of said handle at a fixed point thereon for shifting said handle outwardly only, and means including a separately controlled cable operatively associated with the outer end of said dipper 115 handle for controlling such shifting movement and for shifting said handle inwardly.

10. In a power shovel the combination with a boom, a dipper and dipper handle mounted thereon for swinging and bodily lengthwise shifting movements, a dipper hoisting cable operatively associated with said dipper and dipper handle at a fixed point thereon to swing said dipper and dipper handle and at another fixed point there- 120 125 130

on to shift said dipper and dipper handle in one direction only, and a second cable operatively associated with said dipper and dipper handle for controlling such shifting 5 movement and for shifting said dipper and dipper handle in the opposite direction.

11. In a power shovel the combination of a boom, a dipper and dipper handle mounted thereon for swinging and bodily lengthwise 10 shifting movements, a dipper hoisting cable operatively associated with said dipper and dipper handle at a fixed point thereon to swing said dipper and dipper handle and at another fixed point thereon to shift said 15 dipper and dipper handle outwardly only, and a second and separately controlled cable operatively associated with said dipper and dipper handle for controlling such shifting movement and for shifting said dipper and 20 dipper handle inwardly.

12. In a power shovel, the combination of a boom, a dipper and dipper handle, a pivotal support on said boom in which said handle reciprocates and with which it swings, 25 a shipper shaft, sheaves on said shaft, a retracting cable passing over one of said sheaves and operatively connected to the dipper and dipper handle at a fixed point to retract the dipper and control outward 30 movement of said handle, a hoisting drum, a pair of sheaves on the outer end portion of the boom, a padlock sheave on the dipper handle, and a cable passing from said drum over one of said sheaves on the outer end 35 of said boom and beneath said padlock

sheave and over the other sheave on the outer end of the boom, over the other sheave on said shaft and operatively connected to the upper end portion of said dipper handle at a fixed point thereon whereby to hoist the 40 dipper and move it outwardly.

13. In a power shovel, the combination of a boom, a dipper and dipper handle mounted thereon to swing and shift bodily lengthwise with respect thereto, sheaves at the outer 45 portion of the boom, a hoisting sheave on the dipper, a dipper-hoisting-and-thrusting cable having engagement with said handle and acting lengthwise thereof for thrusting it outwardly and running over said sheaves 50 on the boom with a portion between said sheaves moving on said hoisting sheave, and a separately controlled cable for controlling the outward shifting movement and for retracting the dipper.

14. In a power shovel, the combination of a boom, a dipper and dipper handle mounted thereon to swing and shift bodily lengthwise with respect thereto, a pair of separately controlled operating cables 60 respectively connected to the lower and upper end portions of the dipper handle for controlling the lengthwise shifting of said handle, the cable connected to the upper end portion of said handle also having a hoisting connection between the boom and the dipper.

In testimony whereof, I affix my signature.

PAUL BURKE.
